(57) **CLAIM**

The ornamental design for a rocket toy, as shown and described.

DESCRIPTION

FIG. 1 is a perspective view of a rocket toy showing the new design;

FIG. 2 is a perspective view of the body portion of the rocket toy of FIG. 1, shown separately for clarity of the disclosure. FIG. 3 is another perspective view thereof;

FIG. 4 is a front elevation view thereof;

FIG. 5 is a back elevation view thereof;

FIG. 6 is a left-side view thereof;

FIG. 7 is a right-side view thereof;

FIG. 8 is a top plan view thereof;

FIG. 9 is a bottom plan view thereof;

FIG. 10 is an enlarged view of the encircled portion in FIG. 2 thereof;

FIG. 11 is a perspective view of the body portion of the rocket toy of FIG. 1, shown separately for clarity of the disclosure.

FIG. 12 is another perspective view thereof;

FIG. 13 is a front elevation view thereof;

FIG. 14 is a back elevation view thereof;

FIG. 15 is a left-side view thereof;

FIG. 16 is a right-side view thereof;

FIG. 17 is a top plan view thereof;

FIG. 18 is a bottom plan view thereof;

FIG. 19 is an enlarged view of the encircled portion in FIG. 11 thereof;

FIG. 20 is an enlarged view of the encircled portion in FIG. 11 thereof; and,

FIG. 21 is an enlarged view of the encircled portion in FIG. 11 thereof.

The broken lines depict portions of the article that form no part of the claimed design.

The dash-dot-dash boundary lines illustrate the periphery of the enlarged views of the rocket toy and form no part of the claimed design.

1 Claim, 21 Drawing Sheets
